UNITED STATES PATENT OFFICE

2,260,063

LOUD-SPEAKER

John McWilliams Stone, St. Charles Township,
Kane County, and Carleton T. Webler, St.
Charles, Ill., assignors to Operadio Manufac-
turing Company, St. Charles, Ill., a corporation
of Illinois

Application February 28, 1938, Serial No. 193,054

1 Claim. (Cl. 179—115.5)

The invention relates to loud speakers of the electro-dynamic type and has for its primary object the provision of loud speaker construction, of the kind described, which is exceedingly simple in construction and may be quickly assembled.

In a preferred form of the invention, the improved loud speaker comprises a sheet metal housing preferably formed in one piece, which housing comprises a pot cover and a basket member, the pot cover serving as a housing for an electro-magnet and forming also part of the magnetic circuit. In this form of the invention, a part of the pot cover is the sole path of part of the magnetic circuit of the electro-magnet. The basket member is of conventional form and has a frustro-conical diaphragm mounted on it.

Other objects and advantages will become apparent as the following detailed description progresses, reference being had to the accompanying drawing, wherein—

Fig. 1 is a rear elevation of a loud speaker which embodies the invention.

Fig. 2 is a section taken on line 2—2 of Fig. 1, and

Fig. 3 is an enlarged fragmentary section taken on the same line as Fig. 2.

Referring to the drawing wherein a loud speaker embodying a preferred form of the invention is shown, the reference character 10 designates generally a housing member which is formed preferably from one piece of sheet metal. The housing 10 is formed from a magnetic metal as will be readily understood by those skilled in the art. The housing 10 comprises a pot cover 11 having a cylindrical wall 12 and an end wall 13, the end wall 13 being apertured as at 14 to receive one end of a central pole-piece 15. The cylindrical wall 12 is preferably of somewhat enlarged diameter at its open end to provide an annular shoulder 17 within the pot member 11. At its open end, the cylindrical wall 12 terminates in an outwardly extending annular flange 18 which has formed integral with it a frustro-conical wall 19 which terminates in an annular flange 20 to which the outer periphery of a frustro-conical diaphragm 22 is secured by means comprising a felt ring 23 and a plurality of grommets 24. It will be noted that the annular flange 20 has an integral flange 25 projecting forwardly at its periphery, which flange 25 is adapted to center the diaphragm 22 with respect to the frustro-conical wall 19. The frustro-conical wall 19 and the annular flange 20 form a part which is generally called the basket. In this instance,

it is designated generally by the reference character 26.

Secured by adhesive, or any other suitable fastening means, to the annular flange 18 is a disc 21 of flexible material, the disc 21 being provided with a plurality of annular corrugations 28 which increase the flexibility of the disc. The disc 21 has a central aperture 30 and the forward end of a tube 31 is secured in the aperture by adhesive. The tube 31 carries the voice coil 33 which is disposed in the aperture 34 formed in a disc 35 of magnetic metal, the disc 35 being sometimes referred to in the art as the outer pole-piece. It will be noted that the outer pole-piece 35 rests against the annular shoulder 17. In the preferred construction, the outer pole-piece has a press fit with the inner surface of the pot cover.

The pole-piece 15 is cylindrical in form and has its end 15a projecting through the aperture 14 and through an aperture 37 of a disc 38 preferably formed of magnetic material. An annular shoulder 39 formed on the pole-piece 15 abuts against the disc 38. The end 15a of the pole-piece 15 is riveted over the outer surface of the end wall 13, the construction being such that the end wall 13 and the disc 38 are clamped between the shoulder 39 and the riveted over portion of the end 15a. Of course, this construction also insures that the central pole-piece 16 will be secured to the pot cover 11 and correctly positioned therein so that it will be disposed concentrically with respect to the aperture 34 in the outer pole-piece 35.

Interposed between the disc 38 and the outer pole-piece 35 and disposed around the central pole-piece 15 is the usual field coil 40 of the electro-magnetic structure.

It will be noted that the frustro-conical diaphragm 22 has a central integral portion 42 preferably formed integral with the diaphragm and adapted to close the outer end of the tube 31. The periphery of the central portion 42 is secured by adhesive to the central portion of the flexible disc 21. In the preferred form of the invention the disc 21 is not apertured and therefore co-operates with the portion 42 of the diaphragm 22 to seal the pot cover 11 against the entrance of dust.

It will be readily understood that the magnetic circuit comprises the central pole-piece 15a, the disc 38, the end wall 13, the cylindrical wall 12, the outer pole-piece 35 and the air gap between the outer pole-piece and the central pole-piece 15. It is in this air gap that the voice coil 33

reciprocates in accordance with the well known practice.

Obviously, the cylindrical wall 12 of the pot cover 11 is the sole path of the magnetic flux between the end wall 13 and the outer pole-piece 35. Such construction is relatively inexpensive and is particularly adapted for the smaller loud speakers of the kind described.

The housing 10 is preferably stamped or pressed from sheet metal and therefore it is relatively inexpensive. When the apparatus is to be assembled, the central pole-piece and the disc or washer 38 are secured in place after which the field coil is dropped in place around the central pole-piece 15. The outer pole-piece 35 is then pressed into the position illustrated in the drawing, after which the flexible disc 27 and the diaphragm 22 are secured to the structure by adhesive and by the grommets 24. Obviously, the assembly of the apparatus is exceedingly simple.

Secured to the frustro-conical wall 19 of the basket 26 is an output transformer which is designated generally by the reference character 45. The primary winding of this transformer is generally connected to the output circuit of a radio receiving set, or the equivalent. The leads of the secondary winding may be soldered direct-

ly to the leads of the voice coil 33 without the use of terminal strips, eyelets, etc., or any part attached either to the transformer or to the speaker.

While we have shown and described certain embodiments of our invention, it is to be understood that it is capable of many modifications. Changes, therefore, in the construction and arrangement may be made without departing from the spirit and scope of the invention as disclosed in the appended claim, in which it is our intention to claim all novelty inherent in our invention as broadly as permissible, in view of the prior art.

We claim:

In a sound reproducer housing, an integral, ferrous, sheet metal structure comprising a cylindrical pot portion having an apertured closure at one end, a portion of enlarged diameter adjacent its remaining end providing an interior annular shoulder, an outwardly flanged opening providing a surrounding annular shoulder and a frustro-conical diaphragm supporting portion projecting from the outer edge of said flange.

JOHN McWILLIAMS STONE.
